UNITED STATES PATENT OFFICE.

DAVID M. SCHEFFER, OF NEW CASTLE, AND CHARLES F. MARTIN, OF EVANSVILLE, INDIANA.

ECRASEUR.

SPECIFICATION forming part of Letters Patent No. 326,792, dated September 22, 1885.

Application filed June 3, 1885. (No model.)

To all whom it may concern:

Be it known that we, DAVID M. SCHEFFER and CHARLES F. MARTIN, citizens of the United States, respectively residing at New Castle, 5 Henry county, Indiana, and Evansville, in the county of Vanderburg and State of Indiana, have invented certain new and useful Improvements in Ecraseurs, of which the following is a specification, reference being had thereto in the accompanying drawings.

This invention relates to improvements in ecraseurs for castrating animals, and has for its object the severance of the spermatic cord, and to afford a convenient means whereby the 15 necessity of using clamps and searing the parts may be obviated, and whereby, also, the operation of relieving the animal of its testicles or other protuberances may be more speedily performed than in the ordinary manner.

The nature of the invention consists, essentially, in a slotted tube, to which is fitted a slide carrying the ends of a flat-linked chain, which passes through and is closely fitted to a slot provided with friction-rollers. The said 20 slot is formed in a piece of metal attached to one end of the slotted tube, and is placed at right angles to the axis of the said tube. The links of the chain are placed very close to each other, and the edges of the links are square 25 and quite sharp, as are also the upper and lower edges of the slot. The action, therefore, of the chain and slot when any object is placed in the bight of the chain, and the chain is forcibly drawn through the slot by force 30 applied to the slide, is to compress as well as to cut like a pair of shears. Within the slotted tube is a spiral spring, one end of which bears 35 against the slotted piece and the other against the slide, and has the effect to push them apart.

The lower side of the slotted tube is provided 40 with a handle, which extends to near the end of the slotted tube, and terminates in a head forming a part of said slotted tube, and provided with a transverse slot on a line with the axis thereof. To this head and extending into the slots thereof are two pivoted pawls, each 45 provided with spiral springs, which press in an outward direction against thumb and finger pieces, forming a part of said pawls, by 50 means of which the pawls may be turned upon their axes when pressed upon by the thumb

and finger of the operator. These pawls are each cut with screw-threads, which, when the pawls are in normal position, engage with a long screw-threaded rod, one end of which is 55 attached to the slide hereinbefore mentioned, and the other provided with a crank-handle, whereby the rod may be rotated and the slide and chain be forcibly drawn through the chain-slot. This construction permits the threaded 60 portion of the pawls to be instantly disengaged from the screw-rod, and thereby allows it to be moved freely in either direction within and on a line with the axis of the slotted tube simply by pressing upon the thumb and finger 65 pieces.

It should be noted that the thread on the rod, as seen in Figure 5, is converse, so that the rod may be drawn out without the necessity of disengaging the pawls therefrom.

In the drawings forming a part of this specification, Fig. 1 is a plan view. Fig. 2 is an elevation. Fig. 3 is a sectional view of a part of the tube, and shows the chain-slot and friction-rollers. Fig. 4 is a detached view of the 75 slide, having its spring-cover removed therefrom. Fig. 5 is a sectional view of the pawls, the head, and part of the tube. Fig. 6 is an end view of tube and shows the chain-slot. Fig. 7 is a transverse section of the slide and 80 tube.

The letter A indicates the slotted tube; B, the piece of metal having the chain-slot; b, the chain-slot; b', the friction-rollers; C, the chain; D, the slide; D', a spring-cover attached thereto by means of a screw, d. The two ends of the chain C are fitted in recesses in the top of the slide D, and are maintained in place by the spring-cover D'. This spring may be lifted by the thumb and finger of the operator, and 85 thereby release one or both ends of the chain. 90

E is the spiral spring within the slotted tube A. F is the screw-rod, the thread of which is converse for the purpose above set forth; F', the crank-handle thereof; G, the pawls; G', the 95 slotted head; g', the spiral spring.

H is the handle of the instrument.

To operate the device, first place the fingers upon the pawls, disengaging them from the rod; then catch the chain at the loop end and draw 100 it out to its fullest extent, and then place the loop over the protuberance. This disengage-

ment also permits the spring to carry the chain toward the pawls and back through the slot, and thereby form or create sufficient tension to prevent the escape of the protuberance 5 from the grasp of the chain. Now by removing the fingers from the pawls they will engage the rod again, and then by operating the crank to rotate the rod to the right the protuberance is severed. By using the instrument in this way the artery or vein is closed, which prevents bleeding, and therefore obviates resort to cauterizing or ligating, which we have demonstrated and practically done 10 during the recent past.

15 Having described our invention, what we desire to secure by Letters Patent and claim is—

1. An ecraseur consisting of a slotted tube, a slide fitted to the slot of said tube, a flat-linked chain attached to said slide, the bight 20 of which is adapted to be drawn through a slot at one end of and at right angles to the axis of said slotted tube, a spiral spring within said slotted tube, and a screw-rod attached to said slide, having crank - handle, in combination 25 with pivoted pawls threaded at one end, so as to engage with said screw-rod, and having at the other end thumb and finger pieces and spiral springs, for the purposes herein set forth.

2. In an ecraseur, the slide D, adapted to hold the ends of chain C, the end piece, B, having slot b and friction-rollers b', the slotted tube A, and spiral spring E, in combination with screw-rod F, pivoted pawl G, spiral springs g', and head G', as described, and for the purposes set forth. 30

3. In an ecraseur, the combination, with a slotted tube having a transverse slot near one end for the passage of the chain, and the slide fitted to move in said tube, and having a flat-linked chain detachably connected thereto, of a rod having a converse screw-thread and carrying a handle, and the pivoted pawls having threads corresponding to that on the rod, whereby the connection between the pawls is positive in one direction and yielding in the 40 other. 45

In testimony whereof we affix our signatures in presence of two witnesses.

DAVID M. SCHEFFER.
CHARLES F. MARTIN.
